(57) CLAIM

The ornamental design for a golf tee for mat, as shown and described.

DESCRIPTION

FIG. 1 is a perspective view of the golf tee for mat showing our new design;

FIG. 2 is a front view thereof, the rear view being identical to the front view;

FIG. 3 is a left side view thereof, the right side view being identical to the left side view;

FIG. 4 is a top view thereof;

FIG. 5 is a bottom view thereof; and,

FIG. 6 is a cross sectional view taken along line 6—6 of FIG. 5.

The portions shown in broken lines in FIG. 6 are for illustrative purposes only; and form no part of the claimed design.
